(57) CLAIM

The ornamental design for a smoking tip device, as shown and described.

DESCRIPTION

FIG. 1 is an isometric view of a smoking tip device, showing the top end, front, and left side.

FIG. 2 is a front view of the smoking tip device in FIG. 1. FIG. 3 is a back view of the smoking tip device in FIG. 1, opposite the front view of FIG. 2.

FIG. 4 is a left side view of the smoking tip device in FIG. 1.

FIG. 5 is a right side view of the smoking tip device in FIG. 1, opposite the left side view of FIG. 4.

FIG. 6 is a top end view of the smoking tip device in FIG. 1; and,

FIG. 7 is a bottom end view of the smoking tip device in FIG. 1, opposite the top end view of FIG. 6.

The broken lines in FIGS. 1 through 5 depict environmental subject matter only and the broken lines in FIGS. 6 and 7 depict parts of the smoking tip device. All broken lines form no part of the claimed design.

1 Claim, 2 Drawing Sheets
